UNITED STATES PATENT OFFICE

153,456

DESIGN FOR AN AIRPLANE

Wilfrid A. Pulver, Sherman Oaks, and Arthur E. Flock, Van Nuys, Calif., assignors to Lockheed Aircraft Corporation, Burbank, Calif.

Application September 11, 1947, Serial No. 141,309

Term of patent 14 years

(Cl. D71—1)

To all whom it may concern:

Be it known that we, Wilfrid A. Pulver and Arthur E. Flock, citizens of the United States of America, residing at Sherman Oaks and Van Nuys, respectively, in the county of Los Angeles and State of California, have invented a new, original, and ornamental Design for an Airplane, of which the following is a specification, reference being had to the accompanying drawings, forming a part thereof.

Figure 1 of the drawings is a perspective view of an airplane, embodying the new design, as it would appear from a point forward, to the side, and below the airplane while in flight;

Figure 2 is a top view thereof;

Figure 3 is a front elevational view thereof with the landing gear extended; and

Figure 4 is a side elevational view thereof, also with the landing gear extended.

We claim:

The ornamental design for an airplane, substantially as shown.

WILFRID A. PULVER.
ARTHUR E. FLOCK.
